UNITED STATES PATENT OFFICE.

HENRY O. WILKINSON, OF PETTERIDGE, ENGLAND.

CASING FOR CYLINDRICAL DISTRIBUTING-VALVES.

1,304,520.

Specification of Letters Patent. Patented May 20, 1919.

Application filed October 11, 1916. Serial No. 124,994.

To all whom it may concern:

Be it known that I, HENRY ORWIN WILKINSON, a subject of the King of Great Britain, residing at Petteridge, England, have invented certain new and useful Improvements in Casings for Cylindrical Distributing-Valves, of which the following is a specification.

This invention relates to the construction of a casing, or valve chest, adjustable as regards wear for cylindrical valves, whether of sleeve, or piston type, and whether for rotary or reciprocating action; it also embraces means for cooling such a casing when used upon an internal combustion engine.

The object of the invention is to construct a casing of the character described in contact with which the valve works so that the casing may be diametrically adjusted either for fitting, or to take up wear, and further to provide such adjustment in combination with means for keeping the said casing cool.

The invention is applicable to casings of both plain and jacketed character, and I attain the objects desired by the mechanism illustrated in the accompanying drawings, which show the invention with a water cooling jacket as adapted to the rotating sleeve valve described in my concurrent application for a patent in America, Serial No. 124,993, to which it is of particular application.

Figure 1 is a sectional view showing the water jacket; Fig. 2 is a plan of Fig. 1, showing the line of the divisions; Fig. 3 is an end view showing the connecting pipe across the divided casing in elevation; and Fig. 4 is a section through the connecting pipe.

Referring first to Figs. 1 and 2, it will be seen that transverse divisions *a* and *b* are formed, extending about half-way around at either end of the port region of the casing in the upper side away from the ports, such as *E*, Fig. 3, which lead to the cylinders *A*, *B*, *C*, *D*, and that these divisions are connected by the longitudinal division *c*; bosses *d*, *e* are formed at intervals along this joint *c* by which the adjoining sections can be drawn together, owing to the flexibility of the material of the casing, and thus a diametrical adjustment is secured, which allows of a small variation sufficient to obtain accurate fitting of the casing around the ported sleeve *F* which rotates within it.

Preferably a packing strip *g* (see Figs. 3 and 4) is placed in the joint *c* in order to allow of the bolts *f*, *f* being drawn up tight, the strip being replaced by a thinner strip when wear is required to be taken up. 60

Referring to Figs. 3 and 4, *k* is a pipe formed integrally with the outer side *h* of the jacket space *j* and crossing the division or joint *c*, where it is provided with a flexible joint ring *l*, which serves to retain the 65 water, the bolts *f*, *f* also tightening this joint at the same time, as the division *c*.

The pipe *k* shown in the drawing connects the cylinder jacket *G* with the jacket space *j* by a connection not shown and the 70 outlet from *j* is by a special pipe shown at *n*, Fig. 2, which is peculiar to the special type of valve sleeves shown. The water circulation thus proceeds from the cylinder jackets at *G*, through an elongated port *p* 75 to one side of the jacket space *j* and over the pipe *k* to the other side, it being noted that the adjoining ends of the water jacket at the joint *c* are formed integrally with the sides, the jacket at the transverse portions 80 *a*, *b* being formed in the same way.

The drawings show a casing with rigid extensions beyond the divided section, the ends of which are also integral opposite the transverse divisions *a*, *b*; in many cases it 85 will be sufficient if the rigid parts of the casing stop below the points where the transverse divisions *a*, *b* start, leaving the ends of the joint *c* and of the jacket then open; in other cases the rigid portions will only be 90 of the same length as the divided zone, say, when it is simply required to inclose the port area of the valve, in which case the division *c* will wholly divide the casing in a longitudinal direction; correct fit is of most 95 importance over this region and much difficulty has been experienced hitherto in making rotary valves gas tight there. Where possible the longitudinal division is located on the opposite side of the casing to that 100 through which ports are cut.

Having thus described my invention, what I claim as new and desire to secure by Letters Patent is:—

1. In a valve casing, the combination with 105 a working cylinder for the reception of the valve having ports in its periphery in connection with the cylinders of the engine to which the casing is attached, of a side thereon divided by means of a fine space sepa- 110

rating the material of such side in a longitudinal direction approximately over the region of the port area and partially in a transverse direction at the ends of this 5 region, means for slightly contracting the side thus rendered flexible and fastening it in a rigid manner, and rigid cylindrical ends at each extremity of the casing beyond the transverse divisions, substantially as set 10 forth.

2. In a valve casing, the combination with a working cylinder for the reception of the 15 valve having ports in its periphery in connection with the cylinders of the engine to which it is attached, of a jacket partially surrounding the said cylinder, a side of the 20 said cylinder and jacket divided by means of a fine space separating it longitudinally, a passage connected with the jacket on one side of the division, a passage connected 25 with the jacket on the opposite side of the division the ends of the said passages being located at the division somewhat apart but opposite each other, flexible packing material between the said ends, lugs on each 30 side of the said division, and screws therethrough adapted to contract the cylinder slightly utilizing the flexibility of the material so as to compress the flexible packing 35 between the ends of the connecting passages.

3. In a valve casing, the combination with a working cylinder for the reception of the 35 valve having ports in its periphery in connection with the cylinders of the engine to which it is attached, of a jacket partially surrounding the said cylinder, a side of the 40 said cylinder and jacket divided by means of a fine space separating the material in a

longitudinal direction approximately over 40 the region of the port area and partially in a transverse direction at the ends of this region, a passage connected with the jacket on one side of the division, a passage connected with the jacket on the opposite side 45 of the division the ends of the said passages being located at the division somewhat apart but opposite each other, flexible packing material between the said ends, lugs on each side of the said division, screws 50 therethrough adapted to contract the cylinder slightly utilizing the flexibility of the material so as to compress the flexible packing between the ends of the connecting passages, and rigid cylindrical ends at each extremity of the casing beyond the transverse 55 divisions, substantially as set forth.

4. The combination, in a valve casing, of a working cylindrical portion for the reception of the valve embracing one or more 60 ports through one side in connection with the cylinders of the engine to which the casing is attached, with a jacket partially surrounding the said cylindrical portion, a side of the cylindrical portion and jacket 65 opposite the ported side of the former divided by means of a fine space separating it longitudinally, passages connected to the said jacket and having their ends adjoining each other on each side of the said division, 70 flexible packing between the passage ends and solid packing in the side division, and means for slightly contracting and fastening together the sides of the latter so as to form a rigid connection thereof, substantially as and for the purpose set forth.

In testimony whereof I affix my signature.
HENRY O. WILKINSON.
